UNITED STATES PATENT OFFICE.

CHARLES R. MELDRIM, OF CINCINNATUS, AND JOSIAH J. MELDRIM, OF TRUXTON, NEW YORK.

ROUND BOX.

1,215,956.

Specification of Letters Patent. Patented Feb. 13, 1917.

Application filed May 19, 1916. Serial No. 98,592.

To all whom it may concern:

Be it known that we, CHARLES R. MELDRIM, a citizen of the United States, and resident of Cincinnatus, in the county of Cortland and State of New York, and JOSIAH J. MELDRIM, a citizen of the United States, and resident of Truxton, in the county of Cortland and State of New York, have invented a new and Improved Round Box, of which the following is a full, clear, and exact description.

Our invention relates more particularly to a cheese box though capable of use for other purposes.

15 Cheese box bodies as heretofore made have usually been cut or veneered around the log about one-sixth of an inch thick and we have found by actual experience that there is waste of approximately one-third from 20 selected veneer logs and a waste of approximately one-half of veneers made from ordinary good veneer log, owing to the presence of knots and other imperfections which must be trimmed out of the veneer as waste.

25 The prime object of our invention is to overcome the wastage of material and to substitute other and cheaper kinds of wood, elm being now chiefly used, for forming cheese boxes and the like.

30 A further object is to produce at a great reduced cost a box as good as those now produced or better. To obtain the new result we form our improved box of two thin cheese box hoops or thicknesses, each cut 35 one-twelfth of an inch thick, more or less, and we bend, at the same operation, the two hoops laid closely together around the circled head so that the box will be practically the same as if formed of a single hoop.

40 In forming the cover of the box, we produce the depending rim or flange thereof in the same way as the body, employing two thicknesses of hooping or veneer.

In employing the two separate layers, the 45 grain in both layers is made to run around the box, the grain thus running in the same direction in both layers. In assembling the layers of the double hoop box we select the poorer or defective hoops for the inside 50 layer or liner. The two layers are overlapped and fastened by nails or tacks, the layers between the overlapped ends having direct contact with each other and being unglued. The variation of the grain in the 55 two hoops, together with the fastening of

the same by their overlapped ends, results in a box of increased strength and flexibility.

The invention will be particularly explained in the specific description following.

Reference is to be had to the accompanying drawings forming a part of this specification in which similar reference characters indicate corresponding parts in all the views.

Figures 1 and 2 are perspective views of the inner and outer layers forming the body of the box;

Fig. 3 is a perspective view of the said 70 layers, bent into rounded form having their ends overlapped and fastened;

Fig. 4 is a vertical section of the complete box;

Fig. 5 is an enlarged transverse section 75 through the two layers of the body;

Fig. 6 is a plan view of the layers of material from which the rim of the cover is formed.

In carrying out our invention, the body is 80 formed of an outer layer 10 and an inner layer 11 of veneer. The said layers are laid together and with one operation are bent into rounded form, Fig. 3, with the ends overlapping. The overlapped ends are fastened by tacks or nails 12. Between the overlapped fastened ends, the two layers of material are unglued, the opposed surfaces contacting direct with each other.

The grain of the two layers runs in the 90 same direction, that is to say, around the box but there will be a variation in the grain since the respective layers necessarily present the grain differently because the grain cannot be identical in form and position even in two veneers cut from the same log. Moreover, the imperfections of the respective layers will vary in positions.

The usual round head or bottom 13 is employed and a hoop 14 is applied to the 100 body at the bottom, at the exterior, said hoop thus extending over the overlapped ends and being tacked in the usual manner. The hoop 14, preferably, is composed of two thicknesses, the grain of the veneers running 105 as in the body, around the box.

In forming the cover 15, the same is made round as usual, and the flange 16 thereof is produced from two thicknesses of veneer, the same as the body, there being an outer 110

layer 17 and an inner layer 18. The grain of the respective layers runs around the cover so that one thickness will reinforce the other, the same as in the body.

5 We find that by the above described invention we are enabled to reduce the wastage from a possible 50% to approximately 5%, and we produce a box of great strength and flexibility. The employment of the two 10 thicknesses of material, and the grain running in the same direction and around the box, enables us to utilize much cheaper wood than that required for the production of boxes of this character from one thickness of 15 veneer.

Having thus described our invention we claim as new and desire to secure by Letters Patent:

1. A round box of the class described, including a body composed of two thicknesses of veneer bent together into round form, the grain of both thicknesses running in a direction around the body, the ends being overlapped, and fasteners extending through

said overlapped ends, the said thicknesses 25 lying loosely in direct contact with each other between the fastened ends.

2. A round box of the class described, including a body composed of two thicknesses of veneer bent together into round form, the 30 grain of both thicknesses running in a direction around the body, the ends being overlapped, and fasteners extending through said overlapped ends; the material of said thicknesses being in direct contact and un- 35 united except at the overlapping portions together with a round bottom in said body, a hoop around the body at the bottom, said hoop extending over the said overlapped ends and being composed of two layers of 40 veneer with the grain running around the box, and a cover having a depending rim composed of two thicknesses of veneer both of which have the grain running around the cover.

CHARLES R. MELDRIM.
JOSIAH J. MELDRIM.
